United States Patent

Des. 242,297
Patented Nov. 9, 1976

242,297

COMBINED KEY CHAIN AND ORNAMENT

Armando Ortega, 15316 Gard St.,
Norwalk, Calif. 90250

Filed July 31, 1975, Ser. No. 600,648

Term of patent 14 years

Int. Cl. D3—01

U.S. Cl. D87—8

Fig. 1.

Fig. 2.

Fig. 3.

FIG. 1 is a perspective view of a combined key chain and ornament showing my new design;

FIG. 2 is an elevational view thereof; and

FIG. 3 is a bottom plan view thereof.

The side not shown is similar to the side shown.

I claim:

The ornamental design for a combined key chain and ornament, as shown and described.
